UNITED STATES PATENT OFFICE.

HERBERT H. LEDERER, OF CLEVELAND, OHIO.

CUFF.

1,287,054.

Specification of Letters Patent. Patented Dec. 10, 1918.

Application filed March 9, 1918. Serial No. 221,395.

To all whom it may concern:

Be it known that I, HERBERT H. LEDERER, a citizen of the United States, residing at Cleveland, in the county of Cuyahoga and State of Ohio, have invented a certain new and useful Improvement in Cuffs, of which the following is a full, clear, and exact description, reference being had to the accompanying drawings.

This invention relates to cuffs of the folding type and has for its object to provide a double cuff of this type each member whereof may conveniently serve as a cover or pocket for the other, thus enabling the shirt to be used for a period of time required for the soiling of both cuff members. I realize the foregoing object in and through the constructions illustrated in the drawings forming part hereof wherein:—Figure 1 represents an elevation of the interior of a sleeve having my cuff applied thereto, the inner cuff member being folded up at one side; Fig. 2 a similar view showing the manner in which the inner cuff member may be shifted so as to lie within and be pocketed by the outer member; Fig. 3 a view similar to Figs. 1 and 2 showing the arrangement of the cuff members after they have been reversed; Fig. 4 a sectional view showing the cuff members in normal and unfolded position; Fig. 5 a similar view showing the said members folded; Fig. 6 a view similar to Fig. 5 showing the cuff members reversed.

Describing the various parts herein by reference characters, 1 denotes the sleeve of a shirt, the same being shown as open at its lower end and having attached to the outer side thereof a soft cuff 2 and to the inner side thereof a soft cuff 3. The outer cuff member is stitched to the sleeve only at the upper corner portions thereof, as shown at 2^a, the inner portion of the top of the cuff member being cut out, as shown at 2^b. The inner cuff member is stitched to the inner side of the sleeve by means of an upwardly extending central tab 3^a, the upper corner portions of said member extending downwardly, as shown at 3^b, and being unattached to the sleeve. Each cuff member is provided with upper and lower button holes adapted to register when the said members are folded and to receive a cuff button to hold both members in folded and coöperating relation. These button holes are indicated at 4 and 5. In addition, the central portion of the top of the inner cuff member

is provided with a button 6 coöperating with a button hole 7 in the central portion of the outer cuff member to prevent the central portion of said member from sagging when it is used as a pocket for the inner member.

When the cuff is first used, the outer and inner members will be folded outwardly along the line of fold indicated at a—a and the cuff button inserted in the aligned button holes 4 and 5. The cuff member 3 thus forms a cover and pocket for the outer member 2. When the member 3 becomes soiled, the button is removed, allowing the cuff members to open, the button 6 is removed from the button hole 7 and the sides of the inner cuff member 3 may then be folded inwardly and the said member may then be inserted bodily through the slit provided between the central portion of the member 2 and the central portion of the member 3, as indicated in Figs. 1 and 2. This brings the member 3 outside of the member 2. The cuff is again folded outwardly, along the line of fold, which causes the member 2 to form a cover and pocket for the member 3, as indicated in Fig. 6, and the cuff buttons are again inserted in place, holding the cuff members in their now reversed position.

Having thus described my invention, what I claim is:

1. The combination, with a shirt sleeve, of a foldable cuff member secured at the upper corner portions only thereof to said sleeve and a second foldable cuff member secured at the upper central portion to said sleeve, whereby the second cuff member may be drawn through the space provided between the corner portions of the first cuff member.

2. The combination, with a shirt sleeve, of a foldable cuff member secured at the upper corner portions only thereof to one side of said sleeve and a second foldable cuff member secured at the upper central portion to the opposite side of said sleeve, whereby the second cuff member may be drawn through the space provided between the corner portions of the first cuff member.

3. The combination, with a shirt sleeve, of a foldable cuff member secured at its upper corner portions to said sleeve and having a depressed central portion intermediate of such corner portions, and a second foldable cuff member having a central tab secured to said sleeve intermediate of the corner portions of the first cuff and having its upper corners cut away.

4. The combination, with a shirt sleeve, of a foldable cuff member secured at the upper corner portions only to said sleeve, and a second foldable cuff member having a central tab secured to said sleeve intermediate of the corner portions of the first cuff, the corner portions of said second member being cut away whereby said second cuff member may be drawn through the space provided between the corner portions of the first cuff member.

5. The combination, with a shirt sleeve, of a foldable cuff member secured at the upper corner portions thereof to said sleeve and having a central depressed portion between said corner portions, and a second foldable cuff member having a central tab whereby it is secured to said sleeve between the corner portions of the first member and having its upper corners cut away.

6. The combination, with a shirt sleeve, of a foldable cuff member secured at the upper corner portions thereof to said sleeve and having a central depressed portion between said corner portions, and a second foldable cuff member having a central tab whereby it is

secured to said sleeve between the corner portions of the first member, one of said members having a button near its upper end and the other member having a coöperating button hole.

7. The combination in a shirt sleeve, of a cuff member secured at the upper corner portions only thereof to said sleeve, and a second cuff member secured at its upper end and intermediate its corners to said sleeve, the corner portions of said second member being cut away whereby said second cuff member may be drawn through the space provided between the corner portions of the first cuff member.

8. The combination, with a shirt sleeve, of a cuff member secured to said sleeve, and a second cuff member also secured to said sleeve, there being a slit below the point of attachment of one of said cuff members through which such member may be drawn, thereby to permit the reversal of the arrangement of said cuff members.

In testimony whereof I hereunto affix my signature.

HERBERT H. LEDERER.
